ATTORNEY

WITNESS:

John D. Morris

UNITED STATES PATENT OFFICE.

JEROME B. PRUITT, OF TEMPLE, TEXAS.

ATTACHMENT FOR OIL-BURNING ENGINES.

Application filed March 2, 1925. Serial No. 12,781.

In oil burning locomotives the proper supply of fuel can be most accurately determined by the fireman observing the density of the smoke from the fuel in its passage 5 through the smoke stack. The smoke is not easily observable during the night time, and therefore it may be considered the object of this invention to provide a means whereby rays of light will be directed toward the 10 smoke stack so that the fireman can observe the density of the smoke coming therefrom, and as a result regulate the amount of fuel fed to the locomotive, and thereby materially economize in the use of such fuel.

15 A further object is to provide the head-lamp of an oil burning locomotive with a reflector whereby the rays of light from the headlamp will be passed thereon and reflected thereby toward the smoke stack of the locomotive so that the engineer or fireman can observe the smoke in its passage through 20 the locomotive and regulate the amount of fuel accordingly.

With the above objects in view and others 25 which will present themselves as the nature of the invention is better understood, the improvement resides in the construction, combination and operative association of parts such as is disclosed by the drawings 30 which accompany and which form part of this application.

In the drawings:—

Figure 1 is a side elevation of a sufficient portion of an oil burning locomotive to illustrate the application of my improvement 35 thereon.

Figure 2 is a top plan view of the improvement.

Figure 3 is a sectional view on the line 40 3—3 of Figure 2.

Figure 4 is a face view of the mirror or reflector and the attaching brackets therefor.

An oil burning locomotive is indicated by the numeral 1 in Figure 1 of the drawings, 45 the smoke stack therefor by the numeral 2 and the headlamp by the numeral 3.

In carrying out my invention I rivet or otherwise secure on the top of the headlamp casing outwardly directed arms 4.

50 Two parallel arms are employed.

A mirror or like reflector is indicated by the numeral 5. The reflector is preferably of a rectangular shape and has secured adjacent to its ends sectional brackets. The

brackets each comprise plates having hooked outer ends 6 and their inner ends inwardly flanged. Passing through the flanges 7 of the said plates there are adjustable securing means 8. The lower plates on the inner faces thereof have riveted or otherwise secured thereto angle brackets 9 and the outer flanges of these brackets are disposed against the inner faces of the arms 4. Passing through the said longitudinal arms of the brackets 9 and through suitable openings in the arms 4 there are bolt members 10 which are engaged by wing nuts 11. By such arrangement it will be seen that the reflector 5 may be adjustably supported on the fixed arms 4 so that the reflector may be arranged 55 at desired and proper angles to have the upper rays of light from the headlamp 3 directed thereagainst. The light rays are reflected at an upward angle toward the smoke stack 2 so that the fireman can readily observe the density of smoke emitted 60 through the stack.

It is, of course, to be understood that the mirror can be arranged at any desired point 65 with respect to the smoke stack of the locomotive in a position to be best observed by the engineer or fireman.

Also this device is to be used on stokered fired locomotives and would occasion a saving 70 in fuel in coal burning districts.

Having described the invention, I claim:

An attachment for a locomotive head-lamp comprising spaced parallel arms mounted in horizontal position upon the top of the locomotive headlamp, angular members 75 disposed against the forward ends of said arms, bracket members rigidly secured to said angular members, other bracket members arranged adjacent said first named bracket members, a mirror engaged between 80 the first and second named bracket members, and means for adjusting said first and second named bracket members toward each other for securely clamping and holding 85 mirrors of different sizes, and means for adjustably pivotally mounting said angular members upon the forward ends of said arms 90 whereby the mirror may be adjusted to receive light from the headlamp and to reflect 95 said light upon the smoke issuing from the smoke stack of the locomotive.

In testimony whereof I affix my signature.

JEROME B. PRUITT.
